UNITED STATES PATENT OFFICE.

CLARENCE A. MICHEL, OF CLEVELAND, OHIO, ASSIGNOR TO THE GUIDE MOTOR LAMP COMPANY, OF CLEVELAND, OHIO, A CORPORATION OF OHIO.

STOP SIGNAL FOR AUTOMOBILES.

Application filed October 16, 1922. Serial No. 594,703.

This invention relates generally to tail lights for automobiles and more particularly to a combined stop light and tail lamp, the object being to provide a single structure 5 and device capable of displaying the usual tail light signal continuously and for intermittently displaying the stop signal when the car is stopped or the speed thereof materially checked by the application of the 10 brake. Another object of the invention is to provide a combination device of this character which can also be combined with the license carrier plate or arm.

With these various objects in view the 15 invention consists in the novel features of construction and in the manner of combining or arranging the same, all of which will be fully described hereinafter and set forth in the appended claims.

20 In the drawings forming a part of this specification Fig. 1 is a front view of a combination stop and tail light constructed in accordance with my invention; Fig. 2 is a rear view of the same; Fig. 3 is a side 25 view; Fig. 4 is a view of the casing and lamps contained therein, the colored glasses and the frame for carrying the same being removed from the casing; Fig. 5 is a sectional view on the line 5—5 of Fig. 4, the 30 upper lamp socket being shown in elevation; Fig. 6 is a sectional view of the partition guide.

In the practical embodiment of my invention I employ a substantially cylindrical casing 10 which is closed at its rear side and is 35 offset and enlarged at its front and open side as indicated at 10^a. To the rear side of the casing there is rigidly attached the license carrying plate 11 and also a hollow 40 arm 12 to which is attached the tubular support 12^a and through which the conductor wires 13 pass, these conductor wires being connected to a connection plug 14 fitted into a sleeve 15, said sleeve having a flange 15^a 45 by means of which it is attached to the casing and an internally threaded portion 15^b into which screws the collar 16 for the purpose of securely fastening the connecting plug 14. The conductor wires 17 and 18 50 extend from the connection plug 14 and lead to the sockets 19 and 20, respectively which carry the incandescent lamps 19^a and 20^a, the lamp 20^a being preferably of greater candle power than the lamp 19^a. The sockets 19 55 and 20 are connected to a horizontal parti-

tion 21, the socket 19 projecting downwardly and the socket 20 projecting upwardly. The partition 21 extends entirely across the casing and is of substantially the same depth as the casing so that it divides the casing 60 into an upper and a lower compartment, the lamp 20^a being in the upper compartment and the lamp 19^a in the lower compartment. The side edges of the partition 21 fits into channeled guides 22 rigidly connected to the 65 inner sides of the casing at opposite points and the outer ends of the guide pieces 22 are turned laterally inwardly as shown at 22^a and these lateral ears or end portions are apertured and threaded as shown at 22^b for 70 a purpose hereinafter explained. Fitting upon the enlarged end of the casing is a ring shaped frame comprising the cylindrical portion 23 and the plate portion 24, said plate portion 24 having an upper opening 75 25 which is elongated or oval shaped and a lower opening 26 which may be round or oval as preferred and within the frame and opposite the opening 25 is the flat plate of red glass 27 while within the opening 26 is 80 arranged the red glass 28 of lenticular form. These glasses are held to the frame by means of an interior plate 29 which in the upper half thereof has the letters Stop cut therein as indicated at 30 and in the lower half thereof has an opening 31 cut therein corresponding in size and shape with the opening 26. The frame carrying the glasses is connected to the casing by means of screws 32 85 passing through the frame and interior plate and engaging the apertured and threaded ears 22^a as most clearly shown in Fig. 5 and if desired a positioning pin 23^a may be connected to the interior of the ring portion 23 and engage the opening 10^b in the enlarged 90 portion of the casing.

The cut out letters Stop will be in line with the upper lamp 20^a and the lenticular glass 28 will be in line with the lower lamp 19^a and this lamp is continuously burning 100 and consequently the ordinary tail lamp signal will be displayed.

The lamp 20^a is connected with a switch operated preferably from the brake of the automobile and will be illuminated when 105 the car is stopped or when the speed thereof is materially checked by the application of the brakes. The bottom of the casing is preferably provided with an opening 33 normally covered by a piece of transparent ma- 110

terial 34 such as celluloid or similar material held in place by means of a suitable frame 35 connected to the casing by screws or bolts and nuts 36.

5 The ring shaped frame can be quickly and easily detached from the casing when it is desired to remove and replace either of the lamps and, if desired, the partition 21 can be removed whenever occasion may require 10 the same. The supporting arm and its connection to the casing provides a strong and durable support for the casing and by attaching a license carrying plate between the casing and the arm a strong and durable 15 combination article is provided.

Having thus described my invention, what I claim is:

1. In a device of the kind described, the combination with a casing, of guides upon 20 the interior thereof, the outer ends of which are turned laterally and inwardly and having apertures therein, a partition arranged within said guides and dividing the casing

into two compartments, sockets supported by said partition, a ring frame and glasses 25 arranged therein and means for securing said ring frame to the outer ends of said guides together with means for supporting the casing.

2. In a device of the kind described, the combination with a casing, of guides upon the interior thereof, said guides carrying ears at their outer ends, a partition arranged within the guides and dividing the casing into two compartments, said partition 35 carrying sockets and lamps, a ring frame and glasses arranged therein, a plate connected to said ring frame and provided with openings opposite the glasses carried by the frame, means for connecting the ring frame to the ears together with means for supporting the casing.

In testimony whereof, I hereunto affix my signature.

CLARENCE A. MICHEL
